THOMAS MOORE AND PATRICK H. DAY, OF BLOOMINGTON, ILLINOIS.

Letters Patent No. 88,976, dated April 13, 1869.

IMPROVEMENT IN INKING-APPARATUS FOR COLOR-PRINTING.

The Schedule referred to in these Letters Patent and making part of the same.

Be it known that we, THOMAS MOORE and PATRICK H. DAY, of the city of Bloomington, in the county of McLean, and State of Illinois, have jointly invented a new and useful Machine for Improvement in the Art of Printing, said machine being a combined and variable ink-fount and distributing-table; and we do hereby declare that the following is a full, clear, and exact description of the construction and operation of the same, reference being had to the drawings, making a part of this specification, in which—

Figure 1 is a perspective view of the table, marked A, distributing-strips, marked B, ink-founts, G, color-lifting springs, H, secured in place by the hinged-catch C, by the set-screws D, as arranged for work.

Figure 2 is a perspective sectional view of a separate strip, B, and the table A, with color-box G, and color-lifting spring, combined.

Figure 3 is a perspective view of a distributing-strip, B, detached from its color-box, spring, and seat in the table.

Figure 4 is a separate view of the color-box G, or receptacle for ink.

Figure 5 is a detached color-lifting spring, H, with its arch, h', semicircular indentations, 1, 2, 3, 4; and regulating-screw, i.

Figure 6 is a separate view of the hinged catch C and set-screws D, used to secure the strips in their seat in the table.

In the construction of this machine, the table A may be made of either wrought or cast-iron, of one-eighth or one-fourth of an inch in thickness, with flanges turned up at the sides, of a sufficient height (varying with the size of the machine) to secure firmly the strips.

At the front end a flange is also turned backward, to an acute angle, in order to lock firmly the grooved ends of the strips, when they are fitted over it, preparatory to being secured in their places, by the forward and downward pressure of the catch C.

The strips B, fig. 3, may be made of wrought or cast-iron, or type-metal, as the case may be, or as deemed preferable, the forward end rounded off, to afford easy passage to the inking-rollers, and having, near the rear end, a recess, as seen at E, fig. 3, for the reception of the color-box G, and also at the extreme end, a threaded seat, for the screw i, seen in fig. 5, and a notched recess, for the catch C.

These strips may be of variable lengths and heights, according to the size of press for which they are required, accurately squared and smoothed; but the face, or top B, must always be according to "type-standard," varying from "one line pica" to as many "lines pica" required to suit the letters in the "form."

The color-box G, fig. 4, may be constructed of tin or zinc, preferably tin, of the size required to fit the strips, and made movable, by having the bottom extended to fit in grooves in the recess E, fig. 3, or made immovable, and a part of the strip.

The color-lifting spring H, fig. 5, is made of steel, preferably, after the form shown in the drawing in which h' is an arch, turned over the front end,

said arch having, in its rear side, one or two apertures, designated by the numeral 4, according to the width of the spring.

Below this arch, and back of it, are semicircular notches, cut in the spring, marked 1, 2, 3, the better to facilitate the passage of the ink upward, when the spring is pressed down by the inking-roller bearing upon the arched end h'.

The slot in the rear end of the spring is to allow regulation of the amount of ink raised, by drawing back the spring, if too much ink is raised.

To enable a printer skilled in the art to understand the operation of the machine herein described, the color-boxes G are filled with ink, of any color desired, placed in the strips B, and springs adjusted, as seen in the drawing, and then the "form" made up to correspond with the size of the letter in the type-form.

For division between the strips, "quads" or "reglets" either may be used.

Both "forms" being "made up," the type-form is placed upon the press, in such position that the lines of letter are rolled lengthwise, the roller passing from the distributing-strips, charged with ink, directly over the lines of type.

A brief description of the operation of the machine, at work, is as follows:

The inking-roller passes lengthwise over the distributing-strips, (see dotted lines, representing the roller,) and, striking the arches, forces the springs downward into the ink, which, passing through the apertures 1, 2, 3, 4, is lifted up by the springs, and taken up by the roller, and distributed perfectly over the surface of the strips. They, in turn, impart the ink to the rollers which ink the type-form, distributing the color around their circumference, in parallel bands of color, thence to the type, in manifold colors, if desired.

By this method, as many colors as the fancy of the workman dictates can be imprinted, by one form and one impression, or one color only may be used, with great saving over the common method, economy of labor, and improvement in the art of chromo-printing.

This machine can also be used with a common hand-press, and a great variety of card, job, and power-presses.

Having thus described our machine and its operation,

What we claim as our invention, and desire to secure by Letters Patent, is—

1. The construction of a distributing-strip, cut to type-standard, a lifting-spring, and color-box, as herein described.

2. Securing the strips in the table as herein specified, by means of the clamp C and flange P.

THOMAS MOORE.

PATRICK H. DAY.
